UNITED STATES PATENT OFFICE.

GIANNI BETTINI, OF NEW YORK, N. Y.

DESIGN FOR A PICTURE-BEARING DISK.

SPECIFICATION forming part of Design No. 27,214, dated June 15, 1897.

Application filed March 17, 1897. Serial No. 628,054. Term of patent 14 years.

To all whom it may concern:

Be it known that I, GIANNI BETTINI, of the city, county, and State of New York, have invented and produced a new and original 5 Design for a Picture-Bearing Disk, of which the following is a specification.

In the drawing I have illustrated a disk embodying my design.

The feature of my design consists in a disk 10 bearing a series of pictures arranged to succeed one another to form a spiral line. The pictures may be arranged in contiguity with each other, so as to form an unbroken spiral, or they may be arranged to have a gradually- 15 increasing space between succeeding pictures, while from the center of the disk outward they are in contiguity with each other, thus being segregated into a number of series of pictures, the line passing longitudi-

nally through the center of each series coinciding with a radius of the disk, this latter arrangement being shown in the drawing. 20

The essential feature of the design, however, is the arrangement of the pictures on a spiral line. 25

Referring to the drawing, A represents the disk bearing the series of pictures B, arranged in a spiral line.

What I claim is—

The design for a picture-bearing disk, substantially as shown and described. 30

In testimony whereof I have signed my name to this specification in the presence of two subscribing witnesses.

GIANNI BETTINI.
